RAILWAY TRUCK STRUCTURE

Harry M. Pflager, St. Louis, Mo., assignor to General Steel Castings Corporation, Granite City, Ill., a corporation of Delaware

Application September 19, 1938, Serial No. 230,532

12 Claims. (Cl. 105—197)

The invention relates to railway rolling stock and particularly to truck chafing plates, and associated structure, such as may be provided on relatively movable transom and bolster parts.

It has been the general practice to bolt or rivet the chafing plates on the truck bolster and the truck frame to prevent wear upon the bolster and truck frame. These plates, due to constant relative movement of the truck bolster and truck frame, wear rapidly and when worn allow the bolster to play back and forth producing rough riding and noise due to the bolster and frame chafing plates striking together which is very objectionable in the car and therefore the plates have to be renewed from time to time to maintain the clearance between the truck parts at a minimum, thereby preventing excessive jars and shocks due to braking, pulling, and buffing forces.

The main object of the present invention is to provide mechanism which can be readily adjusted while the car is in service to maintain the desired clearance between the bolster and transom at all times without taking the trucks from under the car or disassembling same. Obviously it is desired also to retain the objectives of the ordinary chafing plates which have been used heretofore.

In the accompanying drawings illustrating the invention—

Figure 1 is a top view of one end of a railway truck bolster and the adjacent portion of the truck frame and including the novel chafing plate structure.

Figure 2 is a vertical transverse section taken on the section line 2—2 of Figure 1.

Figure 3 is a vertical section and elevation taken on the line 3—3 of Figure 1.

Figure 4 is a detail drawn to a large scale showing the adjustable chafing plate structure in elevation.

Figure 5 is a similar detail view illustrating another form of the invention.

Figure 6 is a vertical section taken on the line 6—6 of Figure 5.

The truck frame shown in Figures 1 to 4, inclusive, includes a side member or wheel piece 1, and transverse transoms 2 and 3. Preferably these parts are of box-section and merge with each other, being formed by a one-piece casting. It will be understood that this frame is supported upon the truck wheels and axles in the usual manner and these parts are not illustrated as they form no part of the present invention.

Positioned between transoms 2 and 3 is a box-shaped bolster 4, including a center plate 5 adapted to mount the car body in the usual manner.

Bolster 4 is supported by bolster springs 6 carried by the usual truck spring plank 7. Transom 2 is provided near its end with a circular boss 8 facing towards the bolster and having its face in the form of a flat helix inclined from the plane 5 extending perpendicularly to the longitudinal center line of the truck. Boss 8 is provided with a central circular recess 9, and a circular plate-like member 10 has a corresponding trunnion 11 seated in recess 9. The face of member 10 facing boss 8 has a flat helical contour, and the face of member 10 opposing the bolster is parallel to the bolster wall. A bolt 12 extends through member 10 and the adjacent transom wall, and the coil spring 13 is compressed between the 15 inner face of the wall and a nut 14 forming a shoulder on the inner end of the bolt.

Elements 9, 11 and 12 so mount member 10 on member 8 that member 10 may rotate on its axis and, because of the opposing helical faces, 20 be moved longitudinally of the bolt and transversely of the transom to take up any play between the transom and the bolster. Preferably the bolster is provided with a wear plate 15 abreast of member 10 and this wear plate will be 25 of relatively hard metal so that it will stand considerable frictional contact with member 10 before it becomes necessary to renew the wear plate.

Projecting upwardly beyond the circular periphery of member 8 is an elongated lug or ear 16 having a series of apertures 17. Projecting upwardly beyond the circular periphery of member 10 are one or more lugs or ears 18 and 19 each having an aperture adapted to be aligned 35 with one of the apertures 17 in lug 16. A bolt 22 may be passed through the aperture in the rotatable member lug and a selected one of the apertures in the stationary member lug to hold the relatively movable parts in desired relation. 40

It will be understood that bolt 19 is accessible from the side of the truck, and upon its removal member 10 may be rotated on bolt 12 by an operator at the side of the truck to shift the members angularly, and axially, of each other to vary the 45 overall width of the chafing plate structure or, in other words, to vary the bolster clearance distance between transoms 2 and 3.

Transom 3 and the adjacent portion of bolster 4 are shown as having ordinary wear plates 20 and 21 secured in position and serving to reduce wear upon the bolster and transom, respectively. In view of the adjustment provided by the chafing plate at the opposite side of the bolster, it will be unnecessary to replace elements 20 and 21 for 55.

clearance purposes due to wear or to make them adjustable in any manner. The width of lug 18 on the base member of the chafing plate and the spacing of lugs 18 and 19 on the movable member 5 provides for total rotating movement of 90° between the parts when shifted from the position shown in Figure 3 to the position shown in Figure 4, at which time the bearing area between the two parts will be three-quarters of their total 10 area as indicated by the arc 23 in Figure 4.

By providing the bottom plate as a part of the transom or bolster wall, less space will be required for the complete device than would be required if the two parts were formed separately from the 15 bolster and transom and applied thereto. However, the latter construction may be preferred, particularly if it is desired to equip old trucks, and Figures 5 and 6 illustrate such a form of the invention. In these figures the device is shown 20 as comprising a separately formed base plate 30 and an outer plate 31, the base plate being applied to the transom wall 32 and secured by welding as indicated at W, or it may be riveted in place. The bolt 33 and spring 34 function 25 the same as bolt 12 previously described. In this form of the invention the opposing faces of the parts 30 and 31 comprise two helical sections each extending 180° about the axis of the device and when the two parts have been rotated to their 30 maximum offset position, the bearing area between the plates will be one-half of the total area as indicated by the arcs 35 in Figure 5.

It will be understood that the complementary plates with inclined bearing faces may be applied as a unit to the bolster as well as to the 25 transom. If desired, the chafing plate assembly either in the form of a separate unit or as including the truck part as one element, may be provided on both sides of the bolster although 40 ordinarily the application to one side as shown in Figure 1 is sufficient.

The general objectives indicated in the introductory portion of this specification are readily attained by the structures described, but it will 45 be apparent to those skilled in the art that variations in the details may be made without departing from the spirit of the invention and exclusive use of such modifications as come within the scope of the claims is contemplated.

50 What is claimed is:

1. In a railway truck, a truck frame part and a bolster part movable relative to each other and opposing each other longitudinally of the truck, chafing plate structure for taking thrusts between said parts, said structure comprising a member in fixed relation to one of said truck parts and a cooperating member rotatable on said first-mentioned member about an axis extending transversely of said truck parts, said members having helix-like opposing disk faces whereby their relative rotation varies the extent of said structure transversely of said parts, and means for positively holding said members 55 against accidental relative movement.

2. In combination, a railway truck frame part, a relatively movable truck bolster part extending alongside thereof, chafing plate structure on one of said parts, said structure including relatively 60 rotatable members one bearing on the other with their interengaging faces shaped to vary the extent of the structure transversely of said parts when rotated relatively to each other there being means in said structure for holding said 65 members against relative rotation, said structure

being accessible from the side of the truck for effecting relative rotation of said members.

3. In combination, a railway vehicle truck frame part, a relatively movable truck bolster part extending alongside thereof, chafing plate structure, said structure comprising a member in fixed relation to one of said truck parts and a cooperating member rotatable on said first-mentioned member about an axis extending transversely of said truck parts, said members having helix-like opposing faces whereby their relative rotation varies the extent of said structure transversely of said parts, there being means for holding said members against rotation from the desired adjustment. 15

4. In combination, a railway vehicle truck frame part, a truck bolster part extending alongside thereof, a chafing plate device comprising a plate-like member on one of said truck parts and a cooperating plate-like member rotatable on said 20 first-mentioned member about an axis extending transversely of said truck parts, said members having helix-like opposing faces whereby their relative rotation varies the overall thickness of the device, said members having cooperating lugs 25 projecting from said opposing faces, there being a series of apertures in at least one of said lugs for receiving an element projecting from the other of said lugs to hold the members in desired position. 30

5. In combination, a railway vehicle truck frame part, a truck bolster part extending alongside thereof, a chafing plate device comprising a base member on one of said truck parts and a contact member, said base member having a 35 helix-like face and a circular recess at the axis of said face, and said contact member having a cooperating helix-like face bearing on said base member face and having a boss seated in said recess, whereby said contact member is mounted 40 on said base member to rotate about the axis of said helix to vary the overall extent of said device, there being means for holding said members against rotation from the desired adjustment. 45

6. In combination, a railway vehicle truck frame part, a truck bolster part extending alongside thereof, a chafing plate device comprising a base member on one of said truck parts and a contact member, said base member having a 50 helix-like face and a circular recess at the axis of said face, and said contact member having a cooperating helix-like face bearing on said base member face, and a boss seated in said recess, there being means accessible from the outside 55 of the truck for rotating said contact member on said base member about the axis of said helix to vary the overall extent of said device, there being means for holding said members against rotation from the desired adjustment. 60

7. In a railway truck bolster and frame chafing device, a plate-like member having one face arranged for application to a truck bolster or frame vertical web, another plate-like member overlying said first-mentioned member, a bolt extending through the centers of said members and pivotally mounting the second-mentioned member on the first-mentioned member, the opposing faces of said members being disposed in a common helix, there being means accessible from the outside of the truck for rotating said second-mentioned member on said first-mentioned member about the axis of said helix to vary the overall thickness of said device, there being means 70 75

for holding said members against rotation from the desired adjustment.

8. In combination, a railway vehicle truck frame part, a relatively movable truck bolster part extending alongside thereof, one of said parts including an upright wall, a chafing plate member on said wall opposing the other of said parts, a bolt passing through said member and wall, a spring compressed between said wall and a shoulder on said bolt for thrusting said member towards said wall, said member being movable about said bolt as an axis, there being means for shifting said member longitudinally of said bolt, against the pressure of said spring, when said member is moved about said axis, there being means for holding said members against rotation from the desired adjustment.
9. A railway truck frame having a bolster opposing face including a helical portion inclined from the remainder of said face and arranged to mount a bolster engaging chafing plate member having a similarly inclined bearing face.
10. A railway truck frame having a bolster op-

posing face with a portion having a bearing surface inclined from the remainder of said face in the form of a helix, said face being apertured at the axis of said helix to receive a chafing plate mounting element.

11. A railway truck frame having a bolster opposing face with a portion having a bearing surface inclined from the remainder of said face in the form of a helix and said face being apertured at its axis to receive a chafing plate mounting element, there being a lug projecting from said portion and apertured to receive a chafing plate positioning bolt.

12. A railway truck frame having a bolster opposing wall provided with a boss having an outwardly facing helix-like bearing surface, there being a cup-like recess in said boss at its axis for mounting a coacting chafing plate trunnion, there being a lug of restricted area on said wall extending radially of said boss and having a plurality of apertures for selectively receiving a chafing plate positioning bolt.
